MOTOR COMPRESSOR

Raul Pateras Pescara, Paris, France

Application January 5, 1933, Serial No. 650,349
In France July 5, 1932

5 Claims. (Cl. 230—56)

The present invention relates to motor compressors of the type including two opposed compressing cylinders actuated directly by the internal combustion of a fuel.

5 In machines of that type, the inner ends of the pistons reciprocate in a motor cylinder into which the fuel is injected and in which it is subsequently ignited, the whole working on the two stroke principle. The outer ends of the pistons reciprocate in two compression cylinders respectively disposed on opposite sides of said motor cylinder and coaxially therewith. The return stroke of the pistons is produced by the expansion of the air cushions that remain in the clearance spaces of said cylinders at the end of the outstroke.

20 The chief object of the present invention is to provide a motor compressor of that type in which compression of the air for the scavenging of the motor cylinder takes place during the whole of the compression stroke of the pistons.

According to my invention, that result is obtained by providing the pistons with laterally projecting elements adapted to slide in lateral chambers provided in the casing of the compressor, said sliding elements acting as pistons in said chambers which are always in communication with the scavenging air reservoir.

This, and other objects of the present invention, will be better understood from the following description of a preferred embodiment of my invention, with reference to the accompanying drawings, given merely by way of example, and in which:

35 Fig. 1 is an elevational view, partly in section, of a motor compressor according to the present invention;

Fig. 2 is a horizontal axial section of said compressor;

40 Fig. 3 is a composite view, the right hand side of which is a section on the line AB of Fig. 1, and the left hand side of which is a section on the line CD of Fig. 1;

Fig. 4 is a diagram illustrating the operation 45 of the compressor;

Fig. 5 is an elevational view, partly in section, of a complete compressing unit according to my invention.

In the embodiment shown in the drawings, all 50 the stationary parts of the motor compressor form a unit 1 in which the following parts are included:

(a) Three cylinders (compression cylinder 101 provided with longitudinal slots 11 and connected 55 with delivery pipe 105 through outlet valves not

shown in the drawings, motor cylinder 102, the ends of which are provided with cooling fins 24 and with a piece 25 screwed thereon and fitted with packing rings 26, and a second compression cylinder, similar to cylinder 101, and which is 5 shown in Fig. 5);

(b) A chamber 21 carried by each compression cylinder, connected with the atmosphere through openings 20 provided with air inlet valves 19, and connected with the inside of the compression cylinder through port 22;

(c) A casing 104 inclosing a chamber 12 extending along the whole length of the compressor and connected with motor cylinder 102 through ports 14;

(d) A chamber 15 carried by each compression cylinder 101, connected with the inside of said cylinder through ports 30 and with chamber 12 through ports 16 provided with valves 17;

(e) Two longitudinal external recesses provided 20 on either side of said casing 104, closed on the outer side by plates 9, and connected with chamber 15 through ports 18; said recesses are disposed along grooves 11 of compression cylinder 101.

25 Two pistons, such as 2, are fitted in said cylinders in such manner that their outer ends reciprocate in the compression cylinders respectively and their inner ends (of reduced section) reciprocate in motor cylinder 102. The inner 30 faces of the enlarged ends of the pistons are provided with an annular recess 27 for receiving the end of the motor cylinder.

The pistons are connected together through rods 3 pivoted at one end about journals 4 provided on the pistons, and at the other end to cranks 5 pivoted about journals 6 fitted in unit 1.

Journals 4 also carry sliding members 7 adapted to reciprocate in a piston like manner in guiding recesses 8. The inner face of said sliding 40 members is provided with a plate 10 adapted to cover the portion of groove 11 located between said journal 4 and the inner end of said groove.

The operation of the apparatus will be better understood by referring to the diagram of Fig. 4 45 in which the pressures in one of the compression chambers are plotted in ordinates and the displacements of the corresponding piston are plotted in abscissas.

The piston starts from its innermost position 50 corresponding to point M of the diagram. It compresses air until it reaches a position corresponding to point N of the diagram, for which valves 17 open, thus connecting scavenging air reservoir 12 with compression cylinder 101 55

through ports 30, chamber 15, and port 16. From N to O, the piston drives compressed air into the scavenging air reservoir. When the piston reaches a position corresponding to point O, it closes ports 11 and 30 so that there is no longer any connection between the compressed air in the cylinder and chamber 15. From O to P, piston 2 compresses air into the compression cylinder 101. At point K, that is when the pressure in cylinder 101 begins to grow very high, piston 2 covers port 22 so that there is no longer any connection between cylinder 101 and chamber 21. When piston 2 reaches a position corresponding to point P, the outlet valves (not shown in the drawings) open and from P to Q air is delivered into outlet pipe 105 at a constant pressure. When piston 2 is in a position corresponding to point Q, said outlet valves are closed. From Q to R, during the first part of the instroke, the cushion of compressed air remaining in the clearance space of the cylinder expands down to the atmospheric pressure. When piston 2 reaches a position corresponding to point R it uncovers port 22 and valves 19 open. From R to M, the air from the outside enters into the compression cylinders through said inlet valves and ports 22.

The essential feature of the present invention is that, during the whole of the outstroke of piston 2 auxiliary pistons 7 compress air in chambers 8, which are always in communication with scavenging air reservoir 12 through ports 18 and 16, said pistons 7 continuing their compressing action even when pistons 2 have covered ports 11, which increases the amount of air delivered to the scavenging air reservoir and the pressure of said air.

Plates 10, which are carried by said pistons 7, serve to prevent the lubricating oil, which is abundantly supplied to the guiding recesses 8 and to the connecting rods, to mix with the lubricating oil of pistons 2, which may be reduced to a minimum, owing to the absence of any pressure on the walls of the cylinder.

While I have described what I deem to be a practical and efficient embodiment of my invention, it should be well understood that I do not wish to be limited thereto as there might be changes made in the arrangement, disposition and form of the parts without departing from the principle of my invention as comprehended within the scope of the appended claims.

What I claim is:

1. In a motor compressor including a motor cylinder, two compression cylinders disposed on opposite ends thereof and coaxially therewith, two opposed pistons the inner ends of both of which reciprocate in the motor cylinder and the outer ends of which reciprocate in the compression cylinders respectively, the combination of a reservoir for the compressed air for scavenging the motor cylinder, an auxiliary cylinder fixed on one side of each compression cylinder and connected to said reservoir, auxiliary pistons, operatively connected with the first mentioned pistons, fitted in said auxiliary cylinders, so as to com-

press air therein during the whole of the outstroke of the first mentioned pistons, and articulated means for synchronizing the movements of the opposed pistons, said articulated means being operatively connected with said auxiliary pistons. 5

2. In a motor compressor including a motor cylinder, two compression cylinders disposed on opposite ends thereof and coaxially therewith, and two opposed pistons the inner ends of both of which reciprocate in the motor cylinder and the outer ends of which reciprocate in the compression cylinders respectively, the combination of a reservoir for the compressed air for scavenging the motor cylinder, an auxiliary cylinder fixed on one side of each compression cylinder in parallel relation therewith and connected to said reservoir, auxiliary pistons adapted to reciprocate in said auxiliary cylinders, said compression and auxiliary cylinders being provided with slots parallel to their axes, pins rigidly fixed to said 20 first mentioned pistons and extending through said slots so as to drive said auxiliary pistons, whereby air is compressed in the auxiliary cylinders during the whole of the outstroke of the first mentioned pistons, and articulated means for 25 synchronizing the movement of the opposed pistons, said articulated means being operatively connected with said auxiliary pistons.

3. In a motor compressor including a motor cylinder, two compression cylinders disposed on opposite ends thereof and coaxially therewith, and two opposed pistons the inner ends of both of which reciprocate in the motor cylinder and the outer ends of which reciprocate in the compression cylinders respectively, the combination of a reservoir for the compressed air for scavenging the motor cylinder, a port in each of said compression cylinders for connecting it with said reservoir, at least one check valve for connecting said port with said reservoir so that compressed 40 air is allowed to flow from said port into said reservoir, an auxiliary cylinder fixed on one side of each of said compression cylinders in parallel relation therewith and permanently connected with said reservoir, auxiliary pistons, operatively 45 connected with the first mentioned pistons, fitted in said auxiliary cylinders so as to compress air therein during the whole of the outstroke of the first mentioned pistons, opposed cranks pivoted to the motor cylinder, and connecting rods articulated at one end to said cranks and at their other ends to said auxiliary pistons.

4. In a device according to claim 2, such slots ending at points spaced from the closed ends of the compression cylinders by such distances that 55 the slots are cut off from the compression cylinders by the pistons before the pistons reach the limits of their strokes.

5. In a device according to claim 2, a plate secured to each of said auxiliary pistons opposite 60 to and covering at least parts of the portions of the slots between the working faces of the auxiliary pistons and the inner ends of the slots.
